UNITED STATES PATENT OFFICE.

ARTHUR J. CUMMER, OF DUBUQUE, IOWA, ASSIGNOR OF ONE-HALF TO BERNARD VICTOR KERPER, OF DUBUQUE, IOWA.

HARROW.

1,293,353.

Specification of Letters Patent.

Patented Feb. 4, 1919.

Application filed July 31, 1918. Serial No. 247,591.

To all whom it may concern:

Be it known that I, ARTHUR J. CUMMER, a citizen of the United States, residing at Dubuque, in the county of Dubuque and State of Iowa, have invented certain new and useful Improvements in Harrows, of which the following is a specification.

This invention relates to that class of harrows which employ a continuous spiral blade as the soil pulverizing instrumentality, one object of the invention being to reduce the weight of the frame and to so arrange the harrow-adjusting devices that the harrow may be set at the desired angle with less effort than is required with the machines now in common use. A further object of the invention is to so construct the harrow that the end thrust will be received upon the inner bearing and to provide a construction which will permit the inner and outer bearings to be readily interchanged when the inner bearing has become worn so that the life of the harrow will be prolonged.

These several objects and such other objects as will incidentally appear in the course of the following description are obtained in such a mechanism as is illustrated in the accompanying drawings, in which—

Figure 1 is a plan view of a harrow embodying my improvements and showing the axes of the blades disposed at a right angle to the draft tongue;

Fig. 2 is a side elevation;

Fig. 3 is a horizontal section through the axis of the blade;

Fig. 4 is a detail transverse section on the line 4—4 of Fig. 1;

Fig. 5 is a detail perspective view of the weight support or trough.

The frame of my improved harrow comprises a draft pole or tongue 1 having a whiffletree or other draft applying devices mounted thereon, as shown at 2. To the rear end of the tongue is secured a seat standard 3 having a seat 4 upon its upper end and a foot rest 5 near its lower end. A trussed beam 6 is secured to the rear end of the tongue and projects from each side thereof, the upper member of the beam extending over the end of the seat standard 3 and the lower member of said beam extending under the tongue, as shown. Obliquely disposed braces 7 extend between the tongue and the beam so that a rigid structure is

produced and the beam will be enabled to withstand the strain imposed upon the free ends thereof. An inverted stirrup 8 is disposed under the rear end of the tongue and is secured thereto by the same bolts which secure the beam and the seat standard to the same, as clearly shown in Fig. 4. The inverted stirrup 8 is provided with a plurality of perforations 9 in its sides and a pin 10 is inserted through and supported in certain of said openings to support a roller 11 between the sides of the stirrup, the function of this construction being presently more fully set forth. Between the members of the transverse beam 6, at the ends thereof, I secure links 12 which extend rearwardly from the beam and are equipped with vertically disposed pintles 13 at their rear extremities, said pintles engaging in socket members 14 secured upon the front sides of the harrow-carrying bars 15 at the centers of the same, as clearly shown in Fig. 1. The said harrow-carrying bars 15 having their end portions bent rearwardly and extended downwardly, as shown at 16, thereby providing a U-shaped support for the harrow between the ends of which the axle and the blade are mounted. To the front sides of the members 15, I secure the truss braces 17 whereby the necessary rigidity is imparted to the structure. To the extremities of the downwardly and rearwardly extending side members 16, I secure castings 18 which are provided with inwardly extending studs or pins 19 and have their outer surfaces convex, as shown at 20, the studs or pins 19 being engaged in sockets at the ends of the axle and the convex surfaces 20 permitting the abutting faces of the castings at the inner ends of the frames to ride easily upon each other in all positions of the harrows and receive the end thrust.

The axle of the harrow consists of a series of spools 21 arranged in axial alignment with their ends in contact and each provided in one end with a socket to receive the inner end of a spoke 22. The spools 21 are fitted upon a long bolt or rod 23 and the ends of this rod or bolt may be secured in any desired manner as by means of a nut 24, so that the spools will be clamped together and will thereby be caused to rotate with the blade and prevent release of the spokes. The blade 25 is a continuous

spring metal ribbon disposed in a spiral around the axle and having its ends secured to end spokes 22 and also secured at intermediate portions of its length to intermediate spokes 22, as will be readily understood with reference to Fig. 3. The ribbon is slightly dished so that when the harrow is drawn over the field and the ribbon is revolving and cutting into the soil the 5 thrust or resistance exerted upon the blade by the soil will be transmitted to the inner bearing thereby permitting the harrow to be more easily adjusted to a desired angle. At 10 each end of the axle is a socket or bearing member 26 having its closed end abutting the adjacent head of the end spool 21 and receiving the end of the bolt or rod 23. Within the socket member 26 I fit a bearing block 27 which is axially bored to receive 15 the trunnion 19 and is also provided with an oil passage 28 which is adapted to register with the outlet from the oil cup 29 secured upon the socket member 26, as clearly shown in Fig. 3. It will thus be 20 readily understood that the harrow revolves upon a stationary pin or trunnion at each end and lubricant may flow freely to the said trunnion or pin so that the frictional wear will be minimized and the harrow may 25 rotate easily at all times. Should the inner bearing block 27 become worn through long continued use so that the harrow would not rotate freely, the said bearing block may be readily withdrawn and interchanged with 30 the block at the outer end of the axle so that no appreciable time will be lost from the use of the harrow. It will also be understood that the side members 16, being free at their extremities, will be sufficiently 35 resilient to permit them to be readily sprung so as to withdraw the trunnions 19 from the bearing blocks 27 while at the same time they will normally hold said parts in engagement. Should the side members 16 be 40 too heavy to be readily sprung away from the harrow, the bolts by which a casting 18 is secured to the side member may be 45 easily removed temporarily so that the desired separation of the parts may be effected. 50

Upon each side of the draft tongue 1, adjacent the rear end thereof, I fulcrum a hand lever 30 which is equipped with a latch 31 adapted to engage a holding rack or segment 32 secured upon the draft tongue concentric with the fulcrum of the lever. The lower end of the lever depends below the tongue and is pivoted to the front end of a link 33 which extends between the side members 55 of the inverted stirrup 8 and below the roller 11 mounted within said stirrup, the rear extremity of the link being pivoted to an ear or lug 34 projecting forwardly from the harrow-supporting bar 15 at the inner 60 end thereof. This ear or lug may con-

veniently be formed by bending forwardly the inner end of the truss brace 17 which is the construction illustrated in the drawings. It will be readily noted that by oscillating a hand lever, the link 33 connected therewith will be moved forwardly or rearwardly and, consequently, the corresponding harrow-supporting member with the harrow caused to swing about the pivot 13 so that the blade may be easily brought 75 into any desired angle relative to the draft tongue.

The castings 18 are constructed with socket members 35 in which the extremities of the side members 16 are secured and are 80 also constructed with similar sockets 36 which, when the parts are properly assembled, will be vertically disposed, as shown in Fig. 2. These socket members 36 receive the lower ends of standards 37 which 85 have U-shaped supports or heads 38 at their upper ends. One of these standards and heads is provided at each end of each harrow and a trough 39 is disposed longitudinally over each harrow and has its ends 90 resting in and secured to the respectively adjacent heads 38, as shown in Fig. 5. When the soil is packed firmly and is so hard that the harrow blade tends to merely ride on the surface without cutting into the 95 same, weights may be placed in the trough 39 so as to exert pressure through the axle of the harrow and effect the desired penetration.

It is thought the advantages of my improved harrow will be readily understood from what has been said. So far as I am aware, spiral harrows heretofore constructed have employed a frame the full width of the machine so that the weight of the driver and the frame was thrown on the outer ends of the axles and it was, therefore, very difficult to shift the harrows. Moreover, inasmuch as the frame was fastened to the outer ends of the harrows, a long sweep of the 100 lever was necessary to adjust the harrows to the desired angle but inasmuch as it was impossible to provide center bearings for a harrow having a spiral blade, no means of overcoming these disadvantages had been devised prior to my invention. By mounting the harrows midway their ends, as herein shown and described, I am enabled to use a narrower supporting frame and to effect the desired adjustment of the harrows with 105 a shorter sweep of the operating lever inasmuch as both ends of the harrow will move in arcs and, consequently, a slight movement of the adjusting lever will effect a relatively large shifting of the opposite ends 110 of the harrow. As the end thrust on the axle is received on the inner end of the same and this end is protected from sand and dust it will wear longer than if the thrust were received on the collar at the outer end 115 120 125 130

- of the harrow and when the wear upon the boxes becomes noticeable they can be interchanged readily so that practically a new set of bearings will be provided. So far 5 as I am aware, it has not been practicable heretofore to mount weight boxes upon spiral harrows, but by providing the T-shaped end brackets, as herein set forth on each end of the gang or harrow, I am enabled to mount 10 a weight trough upon the harrow so that the desired penetration of the soil may be attained under all conditions. The links 33 are held down by reason of their upper edges riding under the roller 11 so that said 15 links will always be in the proper position to exert a direct pull upon the harrow supporting bar and the roller may be set at any desired height to maintain the harrow in the proper operative position.
- 20 Having thus described the invention, what is claimed as new is:
1. In a spiral harrow, the combination of a frame, a harrow-supporting member pivotally mounted intermediate its ends upon 25 said frame, means for swinging said supporting member about its pivotal mounting, bearings at the ends of said supporting member, an axle secured in and extending between said bearings, spools mounted upon
  2. In a spiral harrow, the combination of a harrow supporting member, brackets at the ends of said member provided with inwardly projecting trunnions, bearing blocks mounted to rotate about said trunnions, 40 socket members receiving said bearing blocks, an axle secured in and extending between said socket members, spools fitted upon said axle, spokes carried by said spools, and a continuous spiral ribbon secured to the 45 outer ends of said spokes.
  3. In a spiral harrow, the combination of a harrow supporting member, brackets secured to the ends of said member and having vertically disposed sockets, a harrow rotatably mounted upon and extending between said brackets, T-shaped members secured in said vertically disposed sockets and rising therefrom, and a trough carried by the upper ends of said T-shaped members. 50 55

In testimony whereof I affix my signature.

ARTHUR J. CUMMER. [L.S.]
